UNITED STATES PATENT OFFICE.

JAMES T. DOUGINE, OF CHICAGO, ILLINOIS.

MOTOR-VEHICLE.

SPECIFICATION forming part of Letters Patent No. 655,829, dated August 7, 1900.

Application filed July 27, 1899. Serial No. 725,220. (No model.)

To all whom it may concern:

Be it known that I, JAMES T. DOUGINE, a citizen of the United States, residing in Chicago, county of Cook, and State of Illinois, have invented certain new and useful Improvements in Motor-Vehicles; and I do hereby declare the following to be a full, clear, and exact description, such as will enable persons who are skilled in the art to which it appertains to make and use the same.

My invention relates to motor-vehicles, more especially to the running-gear and relative appurtenances thereof, by means of which a strong, rigid, and durable construction is produced, and at the same time a very economically-propelled, easily-controlled, and flexible operation is secured.

One object of my invention is to construct the running-gear of a vehicle in such a manner that each wheel may be separately supplied with a distinct and independent source of propelling power.

Further objects of my invention are to provide a running-gear so arranged that each pair of wheels included therein may be placed with reference to their turning axis in lines radiating from a common center around which the vehicle is to turn, the means by which they are so placed being accomplished by the direct operation of a single controlling device in the hands of the manipulator or by supplying a varying quantity or energy to the respective motors, or by both; to provide a means for applying a braking friction to the wheels of the vehicle and coextensively with the moving elements of the driving-motors, and to improve generally the constructions and arrangements of the various parts of the running-gear of a vehicle.

With these and other objects in view, which may hereinafter appear and be more particularly pointed out and specifically claimed, my invention consists in the means shown or their equivalent for carrying into practical execution the objects as above outlined.

One means for practically executing the invention is illustrated in the accompanying drawings, in which—

Figure 1 is a bottom view of the running-gear. Fig. 2 is an elevation of the same with two wheels removed. Fig. 3 is a longitudinal

section taken through lines 33 of Fig. 1. Figs. 4 and 5 are enlarged detailed views of the braking mechanism. Fig. 6 is a view looking from the bottom and a modified mechanism 55 for shifting the bearings carrying the respective traction-wheels. Fig. 7 is a plan view of same, showing the wheels and their respective shafts shifted into a radial position for the purpose of turning the vehicle around a curve 60 of a very short radius. Fig. 8 is a broken-away detail of the two truck-rings, showing the means employed for connecting them together. Fig. 9 is a section through line 99 of Fig. 8.

Fig. 1 shows the running-gear with the propelling and braking mechanism left off. This view is taken looking from the bottom, so as to show more plainly the means employed for shifting the position of the respective wheels 70 and their bearing-shafts. The device consists of two trucks A and B, each containing a single pair of traction-wheels. The large ring a , around the outside circumference of which the traction-wheels $a' a''$ are adapted to 75 be turned, together with the supporting-shaft a^3 , I have termed a "truck-ring." Two segments of a ring of practically-equal diameter $a^4 a^5$ provide bearings for shafts $a^3 a^6 a^7$. An extension of segments a^8 , having a 80 slightly-shorter radius and having gear-teeth cut into its outside circumference, joins the two segments $a^4 a^5$ together. Another extension a^9 similar in character on the opposite side connects the two segments together in 85 like manner, completing a ring. This ring I shall call the "guide-ring," because it is by the operation or movement of this ring or a portion thereof, as will be more fully herein-after explained, that the vehicle is guided. 90 The two segments $a^4 a^5$, joined by $a^8 a^9$, are operatively guided to the bottom of ring a , so that it may be made to turn around the same axis as that of ring a , clips $a^{10} a^{11}$, Fig. 2, being shown associated with a channel that 95 may be cut into the top surface of the said segments as a means for guiding the latter around ring a .

Referring to Figs. 8 and 9, the two rings a and b are joined together by bolt a^{12} , upon 100 which they are free to turn a slight distance, being limited by the stop a^{13} , the object of

the latter being to prevent the gear-segments a^9 b^9 from becoming unshipped when the respective trucks are caused to occupy greatly-different horizontal planes, as when traveling over extraordinarily-uneven roadways.

5 The ring, composed of segments a^4 a^5 a^8 a^9 , may be shifted in its radial position with respect to ring a by means of a pinion a^{14} , which meshes into the gear of segment a^8 and which 10 may be turned by means of the shaft a^{15} and wheel a^{16} . The shaft is loosely attached to ring a , as shown.

15 It is plainly evident that when the guide-ring of truck A is turned into a position by the pinion a^{14} in virtue of the gearing a^9 and b^9 the guide-ring of truck B will be equally moved, so that the two sets of traction-wheels, with their respective shafts, will occupy positions similar to that shown in Fig. 7, the 20 shafts being then radial from a common center. The same position as that shown in Fig. 7 or any intermediate position may be secured by applying the power in unequal quantities to the respective individual 25 motors. For instance, if power be applied only to wheels b^1 and a^2 wheel b^1 would move ahead and b^2 would move backward slightly, while wheel a^2 would move ahead and a^1 would retrograde. If a similar position be desired, 30 with the wheels and shafts radiating from a point on the opposite side, it can be secured by applying power to the two wheels that were inactive in the first illustration or by turning the wheel a^{16} in the proper direction.

35 When the device is in position shown in Fig. 7 and it is desirable to go around a curve of a short radius, the utilization of the power for driving the vehicle in virtue of my peculiar arrangements, associations, and control of 40 the various parts is as economically applied as when the vehicle is traveling constantly in a straight line.

45 Referring to Fig. 7, the bars c and d (shown also in Fig. 6) may be used in lieu of gear-segments a^9 b^9 . They are especially desirable when a longer wheel-base is required than can be obtained when the rings A and B are brought as closely together as shown in the drawings. In this event the king-bolt a^{12} , 50 Fig. 9, may be longer.

The manner of operation of the bars c d is so evident, it is thought, as to require no further explanation.

55 The shaft a^6 (shown in Fig. 1) represents the two motor-shafts for the two motors a^{17} and a^{18} , to the outer end of which are attached the pinions a^{19} a^{20} , respectively. These pinions are meshed into the respective spur-gears a^{21} a^{22} , the latter being firmly attached to the 60 traction-wheels a' a^2 , respectively.

65 The motors (electric motors are shown) are suspended on a stationary shaft a^3 . They are each attached to a cross-bar a^{23} , which is fixed to a vertical pin a^{24} . Through the latter the shaft a^3 passes. The outer end of the cross-bar a^{23} is loosely supported within the groove of the eye-beam ring a . An extension from

each of the motors may also be supported in said groove, as shown. With this construction the motors move in line with the traction-wheels, shaft, and structure attached to the guide-ring or sliding bearings. A disk a^{24} is attached to the motor-shaft a^6 . A brake-shoe a^{25} is suspended from bolt a^{26} and is adapted to exert a frictional contact with the periphery of the said disk. The geared rim a^{21} , which is attached to the wheel a^2 (see Fig. 4) contains an internal replaceable wearing-ring, against which brake-shoe a^{27} is adapted to bear. The arm that carries this brake-shoe is pivotally attached to shaft a^7 . A downwardly-projecting arm a^{28} is attached by a cord or rod a^{29} to a bell-crank lever a^{30} , the horizontal end of which is connected to a push-rod a^{31} , to the upper end of which a foot-plate may be attached. An open spiral spring a^{32} , surrounding a rod a^{33} , which passes freely through arm a^{34} , holds the two arms a^{28} and a^{34} in a practically-fixed relation when the 85 brakes are off—that is, when the brake-shoes a^{25} and a^{27} are not applied to their respective surfaces—but permit their relation to be changed while the brakes are being applied.

I have described the parts contained in and associated with truck A. Those parts that are similarly associated with truck B are identically the same in nature and character. I have therefore designated them with the corresponding numeral with reference-letter b .

The operation of my device is as follows: Let 100 it be assumed that my vehicle is to be driven by storage batteries and electric motors. A rheostat may be included in each separate circuit supplying the motors, and by this means a varying circuit may be supplied to the respective motors, and a general rheostat may be employed for controlling the circuit supplied to the motors, all contained in one common circuit either in parallel or in series. The operation and principles involved, as described, will be readily understood by those persons that are versed in the art to which it appertains.

By the means above described—to wit, by the manipulation of the individual rheostats—the energy supplied to the motors may be individually varied to suit the exigencies of the occasion for the purpose hereinbefore referred to, and by means of the general rheostat the current collectively supplied 115 may be varied for the purpose of controlling the speed of the vehicle.

Where vehicles have wheels provided with rubber tires, I prefer to attach an annulus, preferably a cast-iron ring, to the said wheel 125 concentric therewith and intermediate of the rim and hub and utilize the said annulus for the purpose of applying friction to retard the motion of the vehicle, or, in other words, the ring forms one element of the brake to which a suitable shoe may be applied. I also find it desirable to arrest the velocity of the propelling-armature, so that too great a strain 130 will not be received by the intermediate train

of gearing by which said armature may be attached to said wheels. I therefore provide a brake for the armature and arrange it with reference to the brake on the traction-wheels 5 so that they may both be applied at the same time and by one operation.

When the rod a^{31} is depressed, the rod a^{29} is pulled forward by means of the bell-crank a^{30} . The brake-shoe a^{27} is thereby pressed 10 into frictional contact with the annulus a^{21} . As the arm a^{28} moves forward arm a^{34} also moves forward, bringing into contact brake-shoe a^{25} , carried thereby and disk a^{24} . The open spring a^{32} is the means through which 15 the pressure between the two arms a^{28} and a^{34} is transmitted. This flexible medium between the two brake-shoe arms is needed, as the wear of the friction parts is uneven and it would be practically impossible to bring 20 all of the surfaces into contact without some such yielding connections.

I do not wish to be confined to the exact construction shown and described, as a considerable latitude or variation in the form and 25 arrangement of the various parts may be made without departing from the scope and gist of my invention, and I wish it understood that I reserve to myself the right to use and practice all such variations that may 30 hereinafter be deemed expedient that may fairly fall within the spirit of my invention.

Having described my invention, what I claim as new, and desire to secure by Letters Patent of the United States, is—

35 1. A vehicle running-gear consisting of two pair of traction-wheels, a frame for each pair of traction-wheels, a path around the vertical axis of said frame through which it is adapted to be moved, and an independent motor for each wheel thereof operatively con-

nected thereto and bodily moving therewith, substantially as set forth.

2. A vehicle running-gear consisting of two rings, or equivalent, loosely attached together, a pair of traction-wheels associated 45 with each ring, a frame for supporting said traction-wheels, a path in which said frame moves around its own vertical axis, an independent motor attached to each traction-wheel and a means for independently or collectively controlling said motors, substantially as set forth.

3. In a self-propelled vehicle the combination of a traction-wheel, a friction-surface on said traction-wheel, a brake-shoe adapted to 55 engage with said friction-surface, a propelling-motor adapted to rotate said traction-wheel, a friction-surface on the moving member of said propelling-motor, a means for positively applying the brake to the said traction-wheel, and a yielding connection for applying the brake to the said propelling-motor operated by the same mechanism, substantially as set forth.

4. A vehicle running-gear consisting of two 65 trucks, each truck being provided with a single pair of traction-wheels, a motor attached to and moving with each traction-wheel, a means such as a bolt for connecting said two trucks together, whereby they are rigidly held 70 in a longitudinal direction, but are free to oscillate with respect to each other, substantially as set forth.

In testimony whereof I have signed this specification, in the presence of two subscribing 75 witnesses, this 24th day of July, 1899.

JAMES T. DOUGINE.
